WORK CLAMP

John P. Hobart, Kalamazoo, and Edward C. Krueger, Otsego, Mich., assignors to Hammond Machinery Builders, Inc., Kalamazoo, Mich., a corporation of Michigan

Application February 19, 1937, Serial No. 126,562

12 Claims.

(CL 90—60)

This invention relates generally to work clamps and more particularly to work clamps for sawing and trimming machines of the type used by printers.

5 The main objects of our invention are:

1st, to provide a work clamp that is simple and effective in operation, which is easy to manipulate, and positive in action.

2nd, to provide improved means for detachably connecting the work clamp to the saw table.

3rd, to provide improved means in a work clamp to prevent marring of the parts in operation.

Other objects of this invention, not at this time more particularly enumerated, will be understood from the following detailed description of the same.

An illustrative embodiment disclosing the improvements in work clamps made according to this invention is shown in the accompanying drawing, in which:

Fig. 1 is a top plan view, parts being broken away and shown in section.

Fig. 2 is a fragmentary longitudinal sectional view taken on the line 2—2 of Fig. 1.

25 Fig. 3 is a view in side elevation of the work clamp in operative position.

Fig. 4 is a transverse sectional view on line 4—4 of Fig. 1.

Fig. 5 is a transverse section on line 5—5 of Fig. 1.

30 Fig. 6 is a transverse section on line 6—6 of Fig. 1.

Fig. 7 is an enlarged view in end elevation of the work engaging jaw.

35 Our clamp is an improvement over clamps of the type disclosed in the patents to Walter S. Runnels, 1,582,307, dated April 27, 1926, and to Cornelius Koets, 1,841,822 dated January 19, 1932.

Referring to the drawing, 1 is a base having 40 a longitudinal side wall 2 terminating in opposite end walls 3 and 4. This base is adapted to rest on the table 5 of the sawing and trimming machine. The table 5 is provided with a hole 6 and an inclined edge slot 7, see Fig. 3. The base of the clamp has a depending portion 8 overhanging the table 5 adjacent the slot 7. A stud 9 is threaded through the base portion 8 for longitudinal adjustment and is adapted to engage the inclined slot to hold one end of the base 45 in place on the table. The stud is secured in adjusted position by a lock nut 10.

The end wall 3 of the base is provided with a vertical bearing 11 and has a conical collar 12 secured to the bottom thereof to fit within the 50 hole 6 in the table. The collar has an eccentric

opening 13 in line with the bearing 11. A cam 14 is provided with a shaft 15 extending upwardly through the opening 13 and bearing 11 for rotary movement. Secured to the upper end of the shaft is a finger piece 16 for turning the cam 14 into and out of engagement with the bottom surface of the table 5. The cam 14 is adapted to pass through the hole 6 when aligned with the collar 12. We thus provide a very efficient and effective detachable connection between the clamp and the table. The movement of the finger piece 16 is limited by a stop 17 on the top of the end wall 3.

The end walls 3 and 4 of the base have aligned laterally opening grooves 18 of circular dovetail cross section for slideably supporting an elongated bar 19 secured to the inner side of an elongated plate 20. The longitudinal edges of the plate 20 are flush with the upper and lower surfaces of the end walls of the base. A work engaging jaw 21 is pivoted at 22 to the end of the bar 19.

A block 23 is secured to the bar 19 and has a tongue 24 slideably co-acting with a longitudinal slot 25 in the side wall 2 of the base. Thus 25 the block 23, bar 19 and plate 20 are slideable as a unit relative to the base 1.

The block 23 and the end walls 3 and 4 of the base have aligned bores 26, 27 and 28 for the passage of a rod 29. The bore 26 in the end wall 3 is provided with a plug 30 constituting a stop for the rod 29. A barrel 31 is secured to the end wall 4 and is provided with a closure 32. Disposed in the barrel between the closure 32 and the outer end of the rod 29 is a compression spring 33 acting to resiliently bias the rod 29 toward the plug 30. Thus the rod 29 is free to be moved longitudinally to a limited extent against the force of the compression spring 33.

On the rod 29 for slideable movement is provided a yoke 34 having a longitudinal bore for the passage of the rod. A wedge 35 is pivoted at 36 to the yoke midway of the ends thereof and has a curved surface 37 adapted to quickly engage the rod and draw the bottom half of the bore 38 into uniform clamping relation with the rod throughout the length of the yoke. This is a very important feature of my invention.

The block 23 and yoke 34 are resiliently drawn toward each other by means of a compression spring 39 acting on a screw member 40 threaded in the block and having its head 41 in a bore 42 in the yoke, see Fig. 2. This arrangement provides a very effective connection between the yoke and the block.

A hand lever 42, having a ball grip 43, is pivoted at 44 to the top of the block 23, and is held in inclined upright position by means of a compression spring 45 having one end bearing against the block and the other end against the lever. The lever 42 is connected to the wedge 35 by means of a link 46, the link being connected to the lever at 47 and to the edge at 48. With the parts in the position shown in Fig. 2, the jaw bar 19 may be adjusted longitudinally relative to the base 1 by pulling or pushing the hand lever 42 as desired. Thus the jaw 21 is moved into engagement with the work, and the hand lever is swung downwardly to a substantially horizontal position as shown by Fig. 3.

The initial movement of the hand lever causes the link 46 to turn the wedge 35 into locking engagement with the rod 29. Continued downward movement of the hand lever causes the connection 47 between the link and lever to be raised into a substantially horizontal position, as shown by Fig. 3, forcing the spring 33 to act through the parts on the work engaging jaw 21 to hold the work in effectively clamped position. The work is released by merely touching the lever to break the toggle lock formed by the positioning of the centers 44, 47 and 48 in substantially the same plane.

From the above description of our work clamp 30, it will be apparent to those skilled in the art that we provide one which is very effective and efficient, easy to mount and remove from the table, and simple to manipulate.

We claim:

35. 1. A clamp comprising a base having a longitudinal side wall terminating in opposite end walls, an elongated bar slideably engaging said end walls so that the parts are held in assembled relation with the bar freely moveable longitudinally relative to the base, a work engaging jaw on the end of said bar, a block secured to said bar, said end walls having aligned bores, a rod extending through said bores for limited longitudinal movement, spring means resisting longitudinal movement of said rod relative to the base, a yoke normally moveable relative to said rod, a wedge pivoted to said yoke and being normally out of engagement with said rod, a hand lever pivoted to said block, a link connecting said lever to said wedge, spring means between said block and lever acting to hold said lever, in its normal position, and spring means urging said block and yoke together, operative movement of said lever first causing said link to actuate said wedge into locking engagement with said rod and then forcing the yoke away from the block so that the action of the spring means on the rod is transmitted to said work engaging jaw, the connection between the link and lever being also moved into 55 the line of centers of the lever pivot and the connection between the link and wedge whereby the force of the block-yoke spring means temporarily holds the parts in such position with the lever substantially horizontal.
60. 2. A clamp comprising a spring biased rod, a jaw bar disposed in spaced parallel relation to said rod, a block fixed to said jaw bar, a hand lever pivoted to said block, means urging said hand lever toward upper inclined position, a yoke slideable on said rod, means acting to urge said block and yoke toward each other, a wedge pivoted to said yoke above said rod intermediate of the length of the yoke and having a cammed surface for smoothly engaging said rod to lock the yoke in place thereon when the wedge is turned

slightly, and link means connecting the hand lever to said wedge so that the latter is turned slightly when the hand lever is swung downwardly toward the horizontal, said last named spring acting to hold the parts temporarily in such position with the wedge, link and hand lever pivots in substantially the same plane. 5

3. A clamp comprising a base, an elongated jaw bar moveably supported at the side of said base, a block fixed to said jaw bar, a hand lever pivoted to said block, means acting to elevate the free end of said hand lever, a yoke, a spring biased rod, a rod engaging wedge pivoted to said yoke to engage said rod between the ends of the yoke, a link connecting said hand lever to said wedge so that when the hand lever is swung downwardly the wedge is turned to engage said bar and lock the yoke and bar together, and spring means urging said block and yoke toward each other and acting to hold the parts in temporarily locked 20 relation when the link and hand lever are substantially in line with one another.

4. A clamp for use with a table having an opening and an inclined edge slot, comprising a base adapted to rest on said table having a depending portion overhanging said table adjacent said slot, a stud threaded through said portion for longitudinal adjustment and adapted to engage said inclined slot to hold one end of said base in place on the table, and a lock-nut on said stud for securing it in adjusted position, the base having a vertical bearing near the other end thereof, a conical collar secured to said base to fit within said hole in the table and having an eccentric opening in line with said bearing, a cam having an eccentric shaft extending upwardly through said opening and bearing, and a finger piece secured to the upper end of said shaft for turning said cam into and out of engagement with the bottom surface of said table, the cam being adapted to pass through said hole when aligned with said collar. 35

5. A clamp for use with a table having an opening and an inclined edge slot, comprising a base adapted to rest on said table and having a depending means adapted to engage said inclined slot to hold one end of said base in place on the table, the base having a vertical bearing near the other end thereof, a conical collar secured to said base to fit within said hole in the table and having an eccentric opening in line with said bearing, a cam having an eccentric shaft extending upwardly through said opening and bearing, and a finger piece secured to the upper end of said shaft for turning said cam into and out of engagement with the bottom surface of said table, the cam being adapted to pass through said hole when aligned with said collar. 50

6. A clamp for use with a table having an opening, comprising a base adapted to rest on said table and having a vertical bearing, a conical collar secured to said base to fit within said hole in the table and having an eccentric opening in line with said bearing, a cam having an eccentric shaft extending upwardly through said opening and bearing, and means secured to said shaft for turning said cam into and out of engagement with the bottom surface of said table, the cam being adapted to pass through said opening when aligned with said collar. 60

7. A clamp comprising a spring biased rod, a jaw bar arranged in spaced parallel relation to said rod, a hand lever pivoted to said jaw bar, a yoke normally slideable relative to said rod and having a longitudinal bearing therefor, a wedge 70

5 pivoted to said yoke midway of the ends thereof and having a curved surface adapted to quickly engage said rod and draw the bottom half of said bearing into clamping relation with said rod throughout the length of the yoke, link means connecting said hand lever to said wedge to turn the latter into engagement with the rod when the hand lever is actuated to move said yoke relative to said jaw bar, and means acting to hold said 10 hand lever in position with the rod connected through said yoke to said jaw bar.

8. A clamp comprising a rod, a block, a hand lever pivoted to said block, a yoke normally slidably relative to said rod and having a longitudinal bearing therefor, a wedge pivoted to said yoke between the ends thereof and having a curved surface adapted to quickly engage said rod and draw the bottom half of said bearing into clamping relation with said rod throughout the length 15 of the yoke, means connecting said hand lever to said wedge to turn the latter into engagement with the rod when the hand lever is actuated to move said yoke relative to said block, and means acting to hold said hand lever in position with the rod connected through said yoke to said block.

9. A clamp comprising a base having end walls provided with aligned bores, a stop in the bore of one end wall, a rod extending through the bore in the other end wall and terminating at 20 said stop, a barrel secured to said last named end wall, and a compression spring disposed in said barrel between the end thereof and the outer

end of said rod so that the rod is resiliently biased toward said stop.

10. A clamp comprising a rod, a yoke normally slidably relative to said rod and having a longitudinal bearing therefor, and a wedge pivoted to 5 said yoke between the ends thereof and having a curved surface adapted when turned to engage said rod and draw the bottom half of said bearing into clamping relation with said rod throughout the length of the yoke without marring the 10 parts.

11. A clamp comprising a base, a rod slidably mounted in said base, means preventing movement of the rod in one direction, spring means tending to prevent movement of the rod in the 15 other direction, a jaw bar disposed for movement in substantial parallelism to said rod's movement, operating means mounted upon said jaw bar, a gripping mechanism slidably received upon the slidably mounted rod, and means cooperatively associated between the operating means and the gripping mechanism whereby the gripping mechanism is rendered effective to grip and also the operating means and the gripping means are moved apart for the purpose described. 20

12. A combination of elements as set forth in claim 11 in which the cooperatively associated means includes a toggle lever connection, said toggle lever connection being movable to substantially straight line position during one phase of 30 its movement.

JOHN P. HOBART.
EDWARD C. KRUEGER.
